His Attorney: J. O'Connell

Patented Sept. 1, 1925.

1,551,840

UNITED STATES PATENT OFFICE.

JOHN W. NASMITH, OF HEATON MERSEY, MANCHESTER, ENGLAND.

COMBING MACHINE.

Application filed February 21, 1924. Serial No. 694,258.

To all whom it may concern:

Be it known that I, JOHN WILLIAM NASMITH, a subject of the King of Great Britain and Ireland, and a resident of 5 Heaton Mersey, Manchester, England, have invented new and useful Improvements in Combing Machines, of which the following is a specification.

This invention relates to combing machines and comprises an improvement in 10 means already described by me in the specification to prior Letters Patents No. 1,466,846 and 1,473,197. In that specification and in the drawings thereto annexed there is shown 15 an arrangement whereby a given quantity of material is fed to the detaching rollers and, when detaching is completed, part of the fed material is withdrawn from behind the top comb into the nipper before the latter closes. 20 In this already patented arrangement the feed apparatus is either a secondary or feed nipper which first feeds and then draws back part of the feed before the nipper closes, or it is a reciprocating roller or rollers having 25 the same object.

The object of the present invention is a feed apparatus which, whilst fulfilling the 30 functions of the arrangement briefly referred to above, will be easily applicable to all combing machines and will be of greatly simplified construction and operation.

The invention will now be fully described in the forms best known to me, with reference to the accompanying drawings 35 wherein:—

Figure 1 is a side elevation partly in section showing the apparatus; and Figures 2 and 3 are fragmentary details, in sectional elevation, of a modification.

40 In Figure 1 feed rollers F F¹ are shown. The lap of material being treated is shown at L, being fed forward by the rollers F F¹. The top roller F¹ is positioned by a bearing E which pivots on a stud 16 and is pressed down upon the lower roller F by spring 45 pressure in any known manner. Upon each side of the bearing block E is formed a projection J which is bored and tapped for the reception of a set screw S. A pair of 50 cranked arms A are pivoted upon a stud O and on this same stud are also pivoted a second pair of cranked arms M which carry a blade B secured to the free ends of such arms by screws S as shown. The arms M 55 bear lugs through which passes a pin 39 and to this pin is attached the rod 40 which may

be controlled in a similar manner to the rod bearing the index 40 in the drawings annexed to the prior specification of Letters Patents Nos. 1,466,846 and 1,473,197 herein- 60 before referred to.

Projecting horizontally from the arms M are ledges G adapted to abut against the upper ends of screws S in the members J when the said arms M are depressed. 65

D are the detaching rollers, T the top comb and P, P² the upper and lower nipper jaws. When the nipper jaw P² as shown is at its nearest point to the detaching rollers the lap L is drawn straight from the feed 70 rollers F F¹ to the top comb T by the rotation of the detaching rollers D. When the nipper swings away from the rollers D the arms M have angular motion around their pivot point O and the blade B descends and 75 depresses the length of lap L to the position shown in dotted lines in Fig. 1, (the feed rollers F F¹ having stopped and conceding no further material), the nipper P then closing down upon the nipper P². By 80 adjusting the screw S the limit of angular traverse of the arms M will be varied owing to the abutment of the ledges G against the ends of said screws, thus regulating the 85 angle to which the lap L is depressed by the blade B, with consequent regulation of the quantity of material drawn back thereby from the top comb T.

In Figure 1 the lap is always at an angle to the horizontal during the feed forward. 90 As shown in the fragmentary sections in Figures 2 and 3 the lap L may be fed forward by a roller F and the nipper P² in a horizontal line, and a recess R provided in the said nipper jaw, the blade B and its 95 operative accessories being provided as before. In Figure 2 the position of the lap and of blade B is shown at the conclusion of the feed stroke, in Figure 3 the blade B has reached the lowest point in its downward 100 stroke and has depressed the lap L into the recess R. By adjusting the screws S as previously described the quantity of material can be regulated by limiting the traverse 105 of the blade B.

I claim:—

1. In a combing machine, a pair of detaching rollers, means for feeding the lap of material to the detaching rollers, a pair of nipper jaws, a blade fitted between the 110 detaching rollers and the feeding means, means for depressing the blade upon the lap

of material to withdraw within the nipper jaws a portion of the projecting tuft of material, and means for limiting the traverse of the blade.

5 2. In a combing machine having the features claimed in claim 1, means for depressing the blade for withdrawal of material within the nipper, such means comprising arms on which the blade is borne, such arms

10 having angular motion around a pivot.

3. In a combing machine having the features claimed in claim 1, a blade and a pair of nipper jaws the lower of which is pro-

vided with a recess into which the lap of material may be depressed by the descending 15 blade.

4. In a combing machine having the features claimed in claim 1, means for regulating the extent of traverse of the blade, such means comprising adjustable screws mounted 20 in the path of members carrying the blade.

In testimony whereof I have hereunto set my hand.

J. W. NASMITH.
